ATTORNEY

UNITED STATES PATENT OFFICE

2,591,786

STOVE ACCESSORY

Richard B. Cronheim, St. Louis, Mo.

Application May 4, 1950, Serial No. 159,960

3 Claims. (Cl. 160—135)

1

This invention relates in general to certain new and useful improvements in a stove-accessory capable of being used as a stove pad or a spatter shield, as desired.

It is one of the primary objects of the present invention to provide a stove-accessory which can be optionally used either as a spatter shield or a stove pad and which may be folded up into a compact relatively thin rectangular unit for storage when not in use.

It is a further object of the present invention to provide a device of the type stated which can be readily unfolded and set upright upon its edges to provide a three-walled or U-shaped enclosure to fit around cooking vessels to catch the spattering grease and food particles which tend to fly outwardly therefrom during certain types of cooking operations.

It is another object of the present invention to provide a combination stove pad and spatter shield which may be economically and efficiently constructed, and is highly attractive in appearance.

It is also an object of the present invention to provide a combined stove pad and spatter shield which is rugged, durable, and easy to clean.

With the above and other objects in view, my invention resides in the novel features of form, construction, arrangement, and combination of parts presently described and pointed out in the claims.

In the accompanying drawings

Figure 1 is a plan view of a stove-accessory constructed in accordance with and embodying the present invention;

Figure 2 is a plan view of the hinge-forming elements and the stove-accessory prior to forming;

Figures 3 and 4 are fragmentary transverse sectional views of the stove-accessory, respectively, along lines 3—3 and 4—4 of Figure 1;

Figure 5 is a perspective view of the stove-accessory in opened-up position for use as a spatter shield; and

Figure 6 is a transverse sectional view of the stove-accessory in folded-up position for use as a stove pad.

Referring now in more detail and by reference characters to the drawing, which illustrates a preferred embodiment of the present invention, A designates a stove-accessory comprising two oblong-rectangular sheets 1, 2, formed of aluminum, stainless steel, or any other suitable metal. At their outer corners, the sheets 1, 2, are preferably rounded off and along their inner

2

transverse margins the sheets 1, 2, are die-cut to provide tabs 3, which are curled to form aligned tubular hinge-eyes 4. Provided for co-operation with the sheets 1, 2, is a similarly shaped central panel 5 also formed of aluminum, stainless steel, or similar metal, and provided along its two longitudinal margins with fold-over tabs 6, the transverse edges 7 of which are cut off at angles of 45°. Along its transverse edges or margins, the central panel 5 is provided with outwardly extending tabs 8 having two spaced rectangular apertures 9 slightly larger in size and for registration with the hinge-forming eyes 4 of the panels 1, 2, respectively. Outwardly of the apertures 9, the tabs 8 are provided with continuous or unperforated sections 10, which are of substantially the same width as the tabs 6 and are similarly leveled off at their transverse margins 11 at complementary angles of 45°.

The tabs 8 are suitably formed to provide tubular hinge-forming eye portions 12 in the sections of metal between, and outwardly beyond, the rectangular aperture 9 and the unperforated outer section 10 is folded inwardly over the transverse marginal portion of the central panel 5 to form a crimping flange for purposes presently more fully appearing.

It will be noted that the hinge-forming eyes 12 will be axially aligned with and embrace the hinge-forming eyes 4, as may be seen in Figure 1 and are swingably connected by a pintle-forming section of wire rod 13.

Provided for disposition upon the under face of the central panel 5 is a sheet of two-ply corrugated paper 14 and a covering sheet of asbestos paper 15, both of which are rectangular in shape and of the same marginal size as the central panel 5. With the corrugated sheet 14 and the asbestos paper 15 laid in place, the marginal tabs 8 are bent over and crimped downwardly upon the edges to hold these sheets in place, as shown in Figure 4. Similarly, the marginal tab portions 10 are crimped downwardly along the transverse edges of the sheets 14, 15, as shown in Figure 3.

It will be noted in this connection that the rectangular edges 7, 11 of the adjacent tabs will meet along diagonal lines to form a smooth but a finer joint and that the tabs 6, 10, will be crimped down tightly and firmly so as to compress the edges of the corrugated paper and the asbestos sheet 15, leaving the main center portion thereof substantially thicker than the diameter of the hinge-forming eyes 4, and 12.

It will also be noted that the diameter of the hinge-forming eyes is such that when the two

side panels 1, 2, are folded over the central panel 5 and upon each other, as shown in Figure 6, the outwardly presented face of the panel 1 will be slightly beyond or tangent to the outermost curve of the adjacent hinge-forming eyes 12 so as to lie flat and smooth. On the other hand, the outwardly presented face of the asbestos sheet 15 will be disposed substantially beyond the adjacent faces of the folded-over tabs 6 and 10 so that when the stove-accessory is folded up to function as a stove pad and set over the stove burner with the asbestos sheet 15 disposed downwardly, the entire structure will rest upon the asbestos sheet 15, and the metallic areas of the device will be spaced substantially upwardly from the stove burner. It will further be noted that when the device is set up for operative use as a spatter shield, the side panels 1, 2 will in effect have inner faces, that is to say, the faces which are presented toward each other in the U-shaped configuration shown in Figure 5, and that these inner faces adjoin the front or forwardly presented face of the central panel 5. By reference, again, to Figure 6 it will be seen that the center-line or axis of the tubular hinge eyes 4 of each of the sheets or side panels 1, 2 respectively, is offset inwardly from the inner face thereof so that the outwardly presented or base portions of the hinge eyes 4 will abut against the longitudinal edges of the slots and the longitudinal edges of the panels 1, 2 between the hinge eyes 4 will similarly abut against the back portions of the hinge eyes 12 thereby preventing the side panels 1, 2 from being accidentally swung rearwardly around and into overlying or folded position upon the asbestos paper 15.

When it is necessary to use the stove-accessory in opened-up position as a spatter shield, the side panels 1, 2, are folded outwardly at approximately right angles to the central panel 5, and the device A set up in shield-forming relation about a stove burner, substantially as shown in Figure 5.

It should be understood that changes and modifications in the form, construction, arrangement, and combination of the several parts of the stove-accessory may be made and substituted for those herein shown and described without departing from the nature and principle of my invention.

Having thus described my invention, what I claim and desire to secure by Letters Patent is:

1. A device adapted to serve alternatively as a spatter shield and stove pad, said device comprising a central panel having a front face, a rear face, opposite side margins, a top margin, a bottom margin, and fold-over tabs along the said margins, the tabs along the top and bottom margins being of substantially equal width, the tabs along the side margins being substantially wider than the tabs along the top and bottom margin and being provided with a series of aligned elongated slots, said last named tabs being bent over to provide axially aligned hinge eyes which extend in spaced relation along each side margin between the slots with the longitudinal edges of each slot extending between the inner portions of the hinge eyes, a heat-insulative covering on the rear face of the central panel, said tabs being folded down marginally upon the covering to hold it in place, a pair of side panels respectively disposed on opposite sides of the central panel along each side margin each of said panels having an inner face and an outer face so that when the device is set up on edge for use as a spatter shield it will form a substantially U-shaped con-

figuration in which the inner faces of the side panels will be presented inwardly toward each other and will adjoin the front face of the central panel, said side panels each being provided along one of its side margins with tubular hinge eyes positioned in axial alignment between the hinge eyes on one of the side margins of the central panel, the hinge eyes of each side panel being curled inwardly and thence around toward the inner face of the side panel so that its axis is spaced inwardly from said inner face and the outwardly presented surface of such hinge eyes in the region where they adjoin the side panel will impinge against the longitudinal edges of the slots to prevent the side panels from being folded backwardly over and upon the heat-insulative covering of the central panel, and hinge pins extending through the aligned sets of hinge eyes, whereby the side panels are swingably connected to the central panel.

2. A device adapted to serve alternatively as a spatter shield and stove pad, said device comprising a central substantially rectangular panel having a front face, a rear face, opposite side margins, a top margin, a bottom margin, and four fold-over tabs along the said margins, the tabs along the top and bottom margins being of substantially equal width, the tabs along the side margins being substantially wider than the tabs along the top and bottom margin and being provided with a series of aligned elongated slots, said last named tabs being bent over to provide axially aligned hinge eyes which extend in spaced relation along each side margin between the slots with the longitudinal edges of each slot extending between the inner portions of the hinge eyes, a heat-insulative covering on the rear face of the central panel, said tabs being folded down marginally upon the covering to hold it in place and being mitered at the four corners so as to lie in smooth-fitting endwise abutting relation, a pair of side panels respectively disposed on opposite sides of the central panel along each side margin each of said panels having an inner face and an outer face so that when the device is set up on edge for use as a spatter shield it will form a substantially U-shaped configuration in which the inner faces of the side panels will be presented inwardly toward each other and will adjoin the front face of the central panel, said side panels each being provided along one of its side margins with tubular hinge eyes positioned in axial alignment between the hinge eyes on one of the side margins of the central panel, the hinge eyes of each side panel being curled inwardly and thence around toward the inner face of the side panel so that its axis is spaced inwardly from said inner face and the outwardly presented surface of such hinge eyes in the region where they adjoin the side panel will impinge against the longitudinal edges of the slots to prevent the side panels from being folded backwardly over and upon the heat-insulative covering of the central panel, and hinge pins extending through the aligned sets of hinge eyes, whereby the side panels are swingably connected to the central panel.

3. A device adapted to serve alternatively as a spatter shield and stove pad comprising a metallic central panel having a front face, a rear face, opposite side margins, a top margin, a bottom margin, and fold-over tabs along the said margins, the tabs along the top and bottom margins being of substantially equal width, the tabs along the side margins being substantially wider than

the tabs along the top and bottom margin and being provided with a series of aligned elongated slots, said last named tabs being bent over to provide axially aligned hinge eyes which extend in spaced relation along each side margin between the slots with the longitudinal edges of each slot extending between the inner portions of the hinge eyes, a relatively thick pad disposed over the rear face of the central panel and consisting of an outer ply of heat-insulative sheet material and an inner ply of compressible sheet material, said tabs being folded down marginally upon the covering to hold it in place and being pressed tightly down so that the pad margins are compressed to a thickness less than the over-all thickness of the pad so that the pad presents an exposed face spaced outwardly from the outwardly presented faces of the folded-over tabs whereby no metal will touch a supporting surface when the device is resting upon the exposed face of the heat-insulative pad, a pair of side panels respectively disposed on opposite sides of the central panel along each side margin each of said panels having an inner face and an outer face so that when the device is set up on edge for use as a spatter shield it will form a substantially U-shaped configuration in which the inner faces of the side panels will be presented inwardly toward each other and will adjoin the front face of the central panel, said side panels each being

provided along one of its side margins with tubular hinge eyes positioned in axial alignment between the hinge eyes on one of the side margins of the central panel, the hinge eyes of each side panel being curled inwardly and thence around toward the inner face of the side panel so that its axis is spaced inwardly from said inner face and the outwardly presented surface of such hinge eyes in the region where they adjoin the side panel will impinge against the longitudinal edges of the slots to prevent the side panels from being folded backwardly over and upon the heat-insulative covering of the central panel, and hinge pins extending through the aligned sets of hinge eyes, whereby the side panels are swingably connected to the central panel.
